UNITED STATES PATENT OFFICE.

SAMUEL KOTZ, OF WASHINGTON, DISTRICT OF COLUMBIA

SIGNAL LIGHT.

Application filed March 24, 1922. Serial No. 546,320.

To all whom it may concern:

Be it known that I, SAMUEL KOTZ, a citizen of the United States, residing at Washington, D. C., have invented a new and useful Improvement in the Signal Lights, of which the following is a specification.

This invention relates to a signal light to be used on automobiles in order to indicate to observers either in front of or in the rear 10 of the vehicle, any change in motion contemplated by the driver of the same.

One of the objects of this invention is to produce such a signal light of simple but durable construction.

15 Another object of this invention is to produce such a signal light of great efficiency consonant with the simplicity of construction used.

Further objects and advantages of this 20 invention will appear from the more detailed description set forth below, in which the accompanying drawing illustrates by way of example by Figure 1, the device in operative position on an automobile; by Figure 2, a rear view of the signal light; by Figure 3, a section through the vertical center of Figure 2; and by Figure 4, a detail of the catch shown.

In the following detailed description, it is 25 obvious that various changes in the structure and in the materials used may be made by one skilled in the art without departing from the spirit or scope of my invention.

In constructing this device, a shell prefer- 30 ably cylindrical in form and made of metal, in two parts, 1 and 2, is hinged as at 3, and further provided with a catch or lock 4 for securing the two halves together. By releasing the catch, the upper part of the shell can 35 be turned on its hinge away from the lower part. The edges of the metal shell are turned in as at 10 and 11 in order to provide lips against which the lenses 5 and 6 rest. The shell halves are also preferably pro- 40 vided with grooves 7 and 8 stamped from the shell members which grooves serve to hold the lenses in position. The lenses 5 and 45 6, are preferably of glass, painted in order to act as indicators. For example, the rear lens 6, as illustrated, preferably shows the word "Stop" together with an extended hand, both in red on a black background. The front lens 5, preferably carries the

word "Turn" and a double headed arrow ←→ both also in red on a black background. 55 Obviously other words and characters may be used in place of or in conjunction with those indicated. The shell is also provided with a conventional lamp socket and base 9, and a lamp 12. Perforations 13, 13 are also 60 preferably provided adjacent the lamp base in the lower half of the shell allowing the passage of wires to the inside of the light case.

It is obvious that the shape of the shell 65 may be cylindrical as illustrated by way of example, or may be varied at will to take other forms without departing from the spirit of my invention. The term "peripheral shell" as used in the claims is intended 70 to cover all of these equivalent forms.

Or to suggest a further modification, a piece of sheet metal, say copper, is stamped to provide ribs or grooves as referred to above and is then bent into the form of say a cylindrical shell. The contacting ends of this shell are then bent over to provide lips which may be gripped together in any desired manner say by rivets, bolts and nuts, etc. In this manner a cylindrical shell in one piece is obtained which holds the lenses in position.

In use the device is permanently or otherwise attached to a proper position, such as the left hand front or rear mud guard, although an intermediate position may be 80 used, by soldering, or removably attached by screws, rivets, etc. The wires controlling the signal light are connected to the usual source of current, which may be the battery of the car or any other convenient source, and the 85 control button placed either on the steering wheel or close thereto. When the operator of the automobile desires to change his motion, he presses the button whereupon the signal light is illuminated and thus warns 90 those in the rear as well as those in front—such as a traffic policeman or approaching automobilist—of his intention. These results are efficaciously accomplished by the exceedingly simple construction set forth. 100

Having now set forth my invention fully, it being understood that obvious changes in the construction or materials may be made by those skilled in the art, I claim—

1. A signal light to be attached to automobiles comprising a cylindrical, peripheral

shell made in two parts hinged together, two coacting parts, hinged together on one side, and adapted to be locked together on the other side, grooves in the shell parts, lenses held in place by the groove edges and a conventional lamp socket and lamp in the base of the shell.

5 2. A signal light to be attached to automobiles, comprising a cylindrical shell made in

SAMUEL KOTZ.
